PLASTERING CONSTRUCTION

Curry Ora Walper, Hamilton, Ontario, Canada

Application June 9, 1933, Serial No. 675,016
In Canada May 6, 1933

2 Claims. (Cl. 72—116)

This invention relates to plastering construction for walls or ceilings and to the method of applying the same.

One of the greatest difficulties experienced with 5 plaster walls and ceilings is found in the tendency of the plaster to crack, due to contraction of the plaster, movement of the walls or ceiling or other causes. The marked tendency is for these cracks to grow or enlarge until the wall or ceiling presents an unsightly appearance and the plaster frequently falls off.

The object of the present invention is to provide a construction wherein this tendency to form cracks is avoided or at least reduced to the extent 15 that any cracks formed in the plaster, due to the mentioned or any other normal causes, are practically invisible in the plastered wall surface. A further object of the invention is to so distribute any unavoidable cracks throughout the 20 plastered surface that they will be so small as to be practically unnoticeable.

In accordance with the invention a series of 25 plaster-sustaining members is disposed on the exposed surface of the lath, upon which the plaster is applied, and these members extend across the spaces between the adjacent lath becoming embedded in the plaster when it is applied to the lath. These plaster-sustaining members are preferably rounded in cross-section and crimped, 30 corrugated or otherwise distorted along their length to insure more secure and firm contact in the plaster.

The invention is illustrated more or less diagrammatically in the accompanying drawing, in 35 which

Figure 1 is a plan view of a construction embodying the invention with the plaster partially broken away;

Figure 2 is a somewhat enlarged sectional edge 40 view of the construction shown in Figure 1, and,

Figure 3 is a view similar to Figure 1 illustrating the invention as applied to another type of lath.

In the drawing, 1 represents lath and 2 the 45 plaster-sustaining members disposed across the lath substantially at right angles to their length. These members are held in position with respect to the lath by means of staples 3 or any other suitable means. The rods 2 are disposed so as to have their adjoining ends overlap and to distribute the joints over the surface, thus to avoid concentration of the effect of cracking stresses in unbroken lines parallel to the plaster keys. There are thus no continuous areas of unreinforced plaster running parallel with the plaster keys, and the stresses are taken up by the independent rods, no stress being transferred from one rod to another. In Figures 1 and 2 the lath shown is of the gypsum board type and is held

in place by means of channels 4 and clips 5 which engage beams or other elements 6, whereas in Figure 3 the ordinary wood lath is shown. In Figure 2 the rods 2 are shown as having a crimped or wavy form to provide greater adherence between them and the plaster. Plaster 7 is applied over the lath and the sustaining rods 2.

The plaster keys formed in the space between the lath are most clearly seen at 8. Cracks in the plaster caused by contraction, movement of the building or otherwise usually form along these portions of the surface and these cracks gradually enlarge with the consequent unsightly appearance. The rods or members 2 support and sustain the plaster coating against the tendency 15 to crack along these lines. Stresses imposed upon the plaster owing to movement in the lath will be distributed and taken up by the sustaining members and cracking will be avoided or very greatly reduced. Moreover, any cracks formed 20 will be widely distributed over the surface along the sustaining members and such cracks will be practically invisible.

Thus it will be apparent that insofar as small cracks are permitted in the plaster the invention 25 contemplates their distribution over the wall surface rather than permitting the accumulation of the disruptive stresses in restricted zones with the formation of large cracks.

It will be observed that the plaster-sustaining 30 members are rod-like independent units used in association with any desired type of lath to which plaster is applied in the construction of wall or ceiling surfaces.

I claim:

1. In a construction wherein a plaster surface is provided, a plaster-anchoring base comprising the combination of a series of laths substantially in parallel spaced relation one to another and a series of substantially rod-like members disposed 40 transversely of the spaces between laths in a plane parallel and adjacent to the faces of the laths substantially independent of the laths and of one another.

2. In a construction wherein a plaster surface is provided, a plaster-anchoring base comprising the combination of a series of laths substantially in parallel spaced relation one to another and a series of substantially rod-like members disposed transversely of the spaces between 50 laths in a plane parallel and adjacent to the faces of the laths substantially independent of the laths and of one another and so arranged that the ends of no three immediately neighbouring members fall on the same straight line drawn trans- 55 versely of said members.

CURRY ORA WALPER.
